UNITED STATES PATENT OFFICE.

GLEN PEPLINSKI, OF MOHAWK, NEW YORK.

INDUCTION-COIL.

1,398,793.

Specification of Letters Patent.

Patented Nov. 29, 1921.

Application filed October 17, 1919. Serial No. 331,414.

To all whom it may concern:

Be it known that I, GLEN PEPLINSKI, a citizen of the United States, residing at Mohawk, in the county of Herkimer and State 5 of New York, have invented new and useful Improvements in Induction-Coils, of which the following is a specification.

The object of my present invention is the provision of an induction coil that is, at once, 10 highly efficient in practice and simple and compact in construction.

To the attainment of the foregoing the invention consists in an induction coil having for its salient feature the arrangement of the 15 primary and secondary coils side by side in annular form about a common core, so that the coils are arranged in close proximity to each other and large surfaces of the coils are exposed to magnetic action.

20 The invention also consists in the peculiar combinations and adaptation of parts as hereinafter described and definitely claimed.

In the accompanying drawings, hereby made a part hereof:

25 Figure 1 is a side elevation of an induction coil constructed in accordance with my invention.

Fig. 2 is a diametrical section of same.

Fig. 3 is an end elevation of the induction 30 coil.

Similar numerals of reference designate corresponding parts in all of the views of the drawings.

By particular reference to Fig. 2, it will 35 be readily appreciated that my novel induction coil comprises a core 1 that is preferably made up of a bundle of soft-iron wires. Surrounding the core 1 are annular spaced heads 2 provided to retain the coils in place.

40 At the inner side of each head 2 is a magnetic member 3 formed by a plurality of sheet iron plates. Intermediate of the said magnetic members 3 and spaced apart are insulating annular members 4 preferably of fiber. At the points 5 are three sections of 45 primary coils, the said sections being connected in series and having their terminals disposed at one end of the induction coil.

The members 3 are, of course, insulated from 50 the adjacent primary coils 5. Intermediate of the primary coils 5 and electrically insulated therefrom by the insulating members 4 are two sections 6 of secondary coils. These sections 6 are connected in series and 55 their terminals are preferably disposed at the opposite end of the induction coil,

Manifestly the described alternation of the primary coil sections 5 and the secondary coil sections 6 may be continued indefinitely according to the capacity that it is desired 60

for the induction coil to possess. The coil sections 5 and 6, the magnetic members 3 and the insulating members 4, are preferably of even diameter, so as to afford a smooth surface, and over such surface is placed insulation 7; the said insulation being preferably formed by a plurality of layers of Empire cloth, tape or other insulating material suitable to the purpose. Surrounding the said insulation 7 is a layer of soft-iron wire 8, 70

which serves in conjunction with the magnetic members 3 to complete the magnetic circuit with a view to utilizing all of the secondary coil. The said magnetic members 3 and auxiliary coil 8, also serve for the conduction of magnetism from parts of the primary coils or coil sections 5 which are not in direct connection with the secondary coil sections 6, to the otherwise uncharged portion of the secondary coils or coil sections close to 80 the core, which renders feasible a comparatively small amount of wire in the secondary, and enables the secondary to come under the full magnetic influence of the core. This contributes to the efficiency of my novel in- 85

duction coil, and the said efficiency is also due in large part to the arrangement of the primary and secondary sections close together, and by the exposure of large surfaces of the said coil sections to magnetic action. 90

Consequently in my improved coil, because of the large amount of surface exposed, the magnetic circuit is extremely short and in consequence the loss of magnetic flux is guarded against and the time necessary for 95 the flux to reach the primary coils or coil sections and to charge the secondary coil sections is reduced. The arrangement of the secondary coil sections alongside the primary coil sections is also advantageous because it 100 contributes to the facility with which the induction coil may be constructed and the facility with which repairs may be made having to do with either primary coil sections or secondary coil sections; it being unnecessary to uncoil the secondary coil sections in order to gain access to the primary coil sections. 105

Having described my invention, what I claim and desire to secure by Letters-Pat- 110 ent, is:

1. An induction coil comprising a core and

alternate annular sections of primary coil and secondary coil arranged side by side about the core, in combination with magnetic members surrounding the core adjacent to the primary coil sections and an auxiliary coil of magnetic material surrounding and insulated from the primary and secondary coil sections and extending adjacent to the magnetic members; said auxiliary coil forming a part of the magnetic circuit.

2. An induction coil comprising a core, spaced heads thereon, annular magnetic members on the core and at the inner sides of the heads, primary coil sections surrounding the core with the outer of said sections adjacent to the magnetic members and also

with the sections connected in series, secondary coil sections surrounding the core intermediate of and alongside the primary coil sections and connected in series, annular insulating members on the core and separating the primary coil sections and the secondary coil sections; said magnetic members, coil sections and insulating members being of even diameter, insulation surrounding the same, and an auxiliary coil of magnetic material surrounding said insulation and extending adjacent to the magnetic members; the said auxiliary coil forming part of the magnetic circuit.

In testimony whereof I affix my signature.
GLEN PEPLINSKI.
